UNITED STATES PATENT OFFICE.

WILHELM ABENDROTH, OF BERLIN-CHARLOTTENBURG, GERMANY, ASSIGNOR TO SIEMENS-SCHUCKERTWERKE GESELLSCHAFT MIT BESCHRANKTER HAFTUNG, OF BERLIN-SIEMENSSTADT, GERMANY, A CORPORATION OF GERMANY.

HYDRAULIC RELAY FOR REGULATING APPARATUS.

Application filed June 9, 1927, Serial No. 197,756, and in Germany June 10, 1926.

My invention relates to a hydraulic relay for regulating apparatus.

When hydraulic relays are employed for regulating apparatus in which the current of the oil under pressure is controlled by a piston slide with controlling edges a peculiar phenomenon may be observed. By the stream and the formation of eddies connected therewith additional forces are developed which oppose the displacement of the piston slide and which may become of such magnitude that the regulating motion is braked to a complete standstill. This phenomenon is the more serious, as in the control gear mentioned apparatus is used on which the highest demands are made in regard to accuracy of operation. If it is desired to avoid the detrimental additional forces which result from hydraulic phenomena, a control gear must be used in which no reciprocating piston slide with controlling edges is employed. In order to attain this end in view I use a tubular member designed in the manner of a rotary slide to which an angular rotation is imparted by the regulating impulse. The rotary slide is located in an inflowing stream of oil and possesses two laterally adjoining chambers. With the two chambers communicate lines which conduct the quantity of oil arriving there each to one side of a piston-like member (control piston, diaphragm or the like). The division of the current of oil is effected in such a way that the rotary slide which is divided into two separate compartments is so turned that the admission opening of the one compartment is enlarged and that of the other compartment reduced. It will be understood that another liquid than oil may be employed.

The drawings affixed hereto illustrate an embodiment of my invention as applied to the control of steam by a pressure impulse. These drawings represent in:

Fig. 1 a sectional elevation of the hydraulic relay,

Fig. 2, an axial longitudinal section with a regulating impulse device, a control piston and a controlled valve,

Fig. 3, a section along line A—B, and

Fig. 4, a section along line C—D both in Figure 1 through the hydraulic relay.

Referring to the drawing, 1 is a diaphragm, which seals a chamber formed by a hood

or in any other manner. To the diaphragm 55 is fixed a jointed rod 2 which with its other end engages a rotary tube 3. The rotary tube 3 is located within a housing 4 and is secured in position in the axial direction by two tubular centers 5 and 6. In the rotary tube 3 are located two transverse radially extending walls 13 and 14 and a transverse axially extending thin wall 17, connecting the inner ends of walls 13 and 14. By these walls the rotary tube is divided into two compartments 15 and 16. To the centers 5 and 6 are joined the pipes 7 and 8 which open into a cylinder 10 at opposite sides of a piston 9.

The motion of the piston 9 is by means of 70 a piston rod 20 and a bell-crank lever 21 transmitted to a valve disc 23. By the adjustment of the valve disc 23 the passage opening of the regulating valve 22 is enlarged or reduced and the steam flowing in 75 the direction of the arrow controlled correspondingly. The chamber behind the regulating valve is in communication with the chamber 25 above the diaphragm 1 by the pipe 24.

Fig. 3 of the drawing shows the arrangement and attachment of the jointed rod 2 at the rotary tube 3 by means of pins and eyes upon the tube.

Fig. 4 shows a section through the hydraulic relay along the line C—D. 3 is the rotary tube, 4 the housing, which is provided with transverse bores 11 and 12. In the rotary tube 3 is furthermore arranged a thin wall 17 in such a manner that in the middle position of the rotary tube it is aligned with the axis of the bores 11 and 12. The bores 11 and 12 are connected by a pipe line 27 with a pump 26.

The manner of operation of my improved hydraulic relay is as follows: For instance, in case of controlling steam the steam entering the chamber 25 sealed by the diaphragm exerts a pressure upon the diaphragm and deflects it downwards to a greater or lesser extent. The jointed rod 2 then adjusts the rotary tube 3 and the thin wall 17 accordingly. Assuming that the rotary valve 3 has turned counter-clockwise into the position shown in dotted lines in Fig. 4. The pipe 11 is then in unrestricted communication with the compartment 15 of the rotary slide valve, while the other compartment 16 is cut off from the

supply. All the pressure oil arriving through the bore 11 thus traverses the compartment 15 and the hollow center pin 5 and reaches the chamber 18 of the cylinder 10 through the pipe 7 so that the piston 9 moves towards the right. The oil in the chamber 19 is discharged through the pipe 8, the tubular center pin 6, the compartment 16 and the bore 12 back to the pump 26. By the piston 9 and by means of the piston rod 20 and the bell-crank lever 21 the valve disc 23 in the steam control valve 22 is moved downwards and the valve opening correspondingly reduced so that a smaller volume of steam passes through the valve opening. The pressure behind the valve consequently drops and correspondingly also in the chamber 25 above the diaphragm. The diaphragm thus takes up a new position. When a regulating motion takes place in the opposite direction the flow of the pressure oil into the chamber 15 is reduced and the flow into the chamber 16 increased, whereby the piston is moved in the opposite direction. The circulation of the oil entering the bore 11 and issuing from the bore 12 is maintained preferably by a rotary pump 26.

The regulating impulse shown as pressure impulse may equally well be designed as temperature impulse, quantity impulse or the like.

My improved relay is suitable for all kinds of regulating purposes, for instance for the regulation of steam generators, the pressure regulation of power plants, for heating plants in the chemical industry and so on.

Various changes and modifications may be made in my invention without departing from its spirit and I desire, therefore, that only such limitations may be placed thereon as are imposed by the prior art.

I claim as my invention:—

1. A hydraulic relay for controlling servomotors or the like by a controlling force, comprising means for circulating an operating liquid, a relay housing and a tubular element rotatably disposed therein and operated by the controlling force, hollow trunnions for holding said element endwise in place and for conducting the operating liquid circulating between the servomotor and the relay, a suitably shaped transverse partition in said element dividing its interior into two compartments and ports in said element and said housing adjacent to said partition, and pressure liquid supply means connected to said ports, said partition dividing the stream of supplied liquid between said compartments in accordance with the angular position assumed by said rotary element to operate the servomotor by the pressure difference between the two divided streams.

2. A hydraulic relay for controlling servomotors or the like by a controlling force, comprising means for circulating an operating

liquid, a relay housing and a tubular element rotatably disposed therein and operated by the controlling force, hollow trunnions for holding said element endwise in place and for conducting the operating liquid circulating between the servomotor and the relay, a transverse partition in said tubular element consisting of two spaced walls extending radially from opposite directions towards the center of the tube and a central axially extending thin wall connecting the two radial walls, said partition dividing the tube interior into two compartments, transverse ports in said element and said housing located in a transverse alignment with said axial wall, and pressure liquid supply means connected to said ports, said central wall dividing the stream of supplied liquid between said compartments in accordance with the angular position assumed by said rotary element to operate the servomotor by the pressure difference between the two divided streams.

3. A hydraulic relay for controlling servomotors or the like, having means for supplying an operating liquid, a rotary oscillating valve element disposed in the liquid stream circulating through said servomotor, and a housing for supporting said valve to permit its oscillation, said housing having transverse ports connected with the liquid supply, said valve element having a suitably shaped transverse partition disposed adjacent to said ports and dividing the interior of said valve into two parts, and means for oscillating said valve on the longitudinal central axis of said housing to divert the stream of supplied liquid between said two parts proportionate to the angular position assumed by said partition with relation to said ports, to operate the servomotor by the pressure difference between the diverted portions of the supply stream.

4. A hydraulic relay for controlling servomotors or the like, having means for supplying an operating liquid, a cylindrical valve element disposed in the liquid stream circulating through said servomotor, and a housing for supporting said valve to permit its oscillation, said housing having transverse ports connected with the liquid supply, said valve element having a suitably shaped transverse partition disposed adjacent to said ports and dividing the interior of said valve into two parts, and means for oscillating said valve on the longitudinal central axis of said housing to divert the stream of supplied liquid between said two parts proportionate to the angular position assumed by said partition with relation to said ports, to operate the servomotor by the pressure difference between the diverted portions of the supply streams.

In testimony whereof I affix my signature.
WILHELM ABENDROTH.
